UNITED STATES PATENT OFFICE.

WILBUR R. BOHLANDER, OF PIQUA, OHIO.

AEROPLANE.

1,355,751.

Specification of Letters Patent. Patented Oct. 12, 1920.

Application filed March 1, 1919. Serial No. 280,016.

To all whom it may concern:

Be it known that I, WILBUR R. BOHLANDER, a citizen of the United States, and a resident of Piqua, in the county of Miami and State of Ohio, have invented certain new and useful Improvements in Aeroplanes, of which the following is a full, clear, and exact description, reference being made to the accompanying drawings, forming part 10 of this specification.

My invention relates to aeroplanes, and has as its object the stabilizing of such planes against tipping and dipping. This object I accomplish by that certain construction 15 and arrangement of parts to be hereinafter more specifically pointed out and claimed, wherein the stabilization is accomplished chiefly by creating counter air currents and utilizing the tendency of the plane to 20 press the air beneath it as the agent for establishing the stability. By this "compression," I refer to the necessary result of the heavier-than-air machine moving through the air.

25 In the drawings,

Figure 1 is a top plan view of a biplane illustrating my invention.

Fig. 2 is a front elevation of the plane.

Fig. 3 is a side elevation thereof.

30 Fig. 4 is a side elevation of a plane on a smaller scale, with air currents or lines of resistance illustrated by lines and arrows.

Fig. 5 is a front elevation with the air depicted in the same manner as in Fig. 4.

35 The aeroplane shown is a biplane, having the lower plane 1, the upper plane 2, and the braces 3. The plane has the body indicated at 4 and the rudder at 5. My invention resides in the construction of the upper plane 40 and in the provision of two stabilizers located at each end of the lower plane.

Taking up first the stabilizers:—they are alike in construction for both sides, and have frames 6 of rectangular shape and as long 45 as the width of the lower plane, said frames being located at the tips of the lower plane so as to lie under the overhang of the upper plane. This position would naturally vary with the make of plane, and the number of 50 planes employed.

The stabilizer frames are covered with suitable cloth on the outer side 7 and the top 8. They are uncovered except along these two sides. The operation of the stabilizer 55 is shown in Fig. 5.

For convenience, the currents of air strik-

ing laterally on the aeroplane are illustrated by the lines x , y and z (each line having arrows thereon to indicate its direction). The current x in striking the right tip of the upper plane (the left in the drawing) will tend to tip the craft to the left. The current y will not affect the tipping appreciably, and the current z , if no stabilizer were present would not be able to counteract the tipping pressure of the current x by pressure on the left tip of the upper plane.

When the current z strikes the stabilizer, however, the air will be forced around from the side 7 to the side 8, which will exert a 70 strong lifting tendency on the left side of the frame intermediate the planes, acting almost at right angles to the horizontal axis of the craft. The down pressure of the machine will add to the pressure of the current z and thus give it additional effect in counteracting the current x which has the advantage of larger wing surface over current z . It can also be observed that the stabilizers function for currents of air coming 75 from the same direction as the tipping current, and that chance currents of air from the tipped end of the craft will be prevented from affecting the tipped-up stabilizer by the interposition of the lower plane in the 80 path of the current.

The upper plane 2 is constructed with the long opening or open space 9 which runs substantially the whole width of the plane. The effect which this opening will have is 90 illustrated in Fig. 4, where the various currents into which a craft could run are intended to be depicted.

When the current "a" strikes the lower plane there is a tendency to lift the craft, 95 but not to cause it suddenly to dip or take a perpendicular dive. The currents which tend to lift the nose of the craft upwardly are those which strike the front part of the upper plane from below indicated at "c," 100 and those which strike the rear part of the upper plane from above marked "e." Those which tend to cause dipping down of the nose, are the currents which strike the rear part of the upper plane from below illustrated at "b," and those which strike the front part of said upper plane from above, indicated at "f." Currents running horizontally are marked g^1 , g^2 and g^3 .

The effect of the slot or opening is to provide a passageway through which the current "c" will rush. This current will rush

upwardly through the opening and will there be met by the horizontal current g^3 and the downward currents e and f , if encountered by the craft. The result of the 5 downward and parallel currents striking the current " c " will be to bend it back as shown at " c^1 " against the rear of the plane 2 and tend to depress the said rear portion. The current at " g^3 ," which is naturally very 10 strong as it directly opposes the movement of the craft, is the chief agent in the turning back of the current at " c^1 ," and the current at " c^1 " counteracts the current " b ."

It should be understood that the currents 15 selected are merely representative of currents acting against the plane from all sources, and that there would be different but similar results for different currents. When the craft starts to tilt nose first, there 20 would always be the currents g and currents c . In addition there would be some one of the danger currents b and f . Ordinarily the current c will be the prevailing current which strikes the craft, since it flies with 25 the nose tilted up in order not to fall by gravity, and the diverting of part of this current to the top of the rear of the upper plane is the stabilizing feature against dipping or diving.

The invention thus provides for the aeroplane a tendency to remain what might be called "even keel" in the air, and to right itself against sudden tipping or dipping. The principle utilized for accomplishing the 35 purpose might be stated as the changing of direction of the air currents or pressure against the under surfaces of the planes or stabilizers, so as to develop a counter tendency to dangerous currents. The means used are the preferred ones as applied to a 40

biplane of the type more or less diagrammatically indicated in the drawings.

Having thus described my invention, what I claim as new and desire to secure by Letters Patent, is:—

45

1. In an aeroplane composed of two or more planes, means for stabilizing the craft against sideward tipping, comprising auxiliary frames mounted on each end of the lower plane underneath the ends of the 50 upper plane and having perpendicular surfaces for redirecting upward currents and lateral surfaces which receive the redirected currents in a lifting direction.

2. In an aeroplane composed of two or 55 more planes, means for stabilizing the craft against sideward tipping, comprising auxiliary frames of rectangular shape and mounted at the tips of the lower plane underneath the upper plane, the auxiliary 60 frame having an outside covering and a top covering, the outside covering acting to redirect upward slanting air currents and turn them directly up against the top covering and thence underneath the upper plane, for 65 the purpose described.

3. In an aeroplane composed of two or more planes, means for stabilizing the craft against nose dipping and diving and sideward tipping, comprising an opening across 70 the upper plane of the craft midway between the front and rear edges thereof and extending substantially from tip to tip thereof together with auxiliary frames mounted on each end of the lower plane 75 underneath the ends of the upper plane and having perpendicular surfaces for receiving the redirected currents in a lifting direction.

WILBUR R. BOHLANDER.
